UNITED STATES PATENT OFFICE.

SIEGMUND CHIGER, OF BERLIN, GERMANY.

SUBTRACTING DEVICE FOR CHANGE-GIVING APPARATUS.

1,078,085.

Specification of Letters Patent. Patented Nov. 11, 1913.

Application filed February 18, 1913. Serial No. 749,171.

To all whom it may concern:

Be it known that I, SIEGMUND CHIGER, a subject of the Emperor of Austria-Hungary, residing at 65 Kurfürstendamm, Berlin, 5 Germany, have invented new and useful Improvements in Subtracting Devices for Change-Giving Apparatus, of which the following is a specification.

The present invention relates to apparatus for giving change or for subtracting, 10 of the kind wherein a movable part corresponds to each figure of the minuend or subtrahend, which movable part is first set in accordance with the value of the corresponding figure of the subtrahend, is then 15 coupled with a device, for instance a disk provided with projections for coupling or actuating the change ejecting devices, and is finally set according to the value of the corresponding figure of the minuend. In devices of the above kind, the disks or members having projections for coupling or bringing into action the change delivering devices, are moved from the zero position 20 through amounts corresponding to the change to be given and are thus brought into the operative positions. This arrangement requires that in subtracting the units, tens or hundreds and so on of the subtrahend from the next higher figures of the minuend, the disks corresponding to the higher figures be moved backward by one 25 division in order that the proper change be delivered.

30 The object of the invention is to obviate the necessity of backwardly rotating or setting the disks. This is obtained in accordance with the invention by arranging the initial positions of the disks corresponding 35 to the tens, hundreds and higher figures as shifted backward by one division usually one tenth of a revolution from the zero positions of the said disks, so that the disks in their initial positions have those projections in the operative positions which serve for coupling or rendering operative the delivering devices of 9 units of the respective figures, that is the pfennig-tens, the mark-units and the mark-tens, and so on. 40 After the disks have been set, suitable devices adapted to be thrown into and out of gear are brought into action and turn the disks forward by one division or one tenth of a revolution.

45 The accompanying drawings show by

way of example one construction of the invention.

Figure 1 is a diagrammatic view of one part of the apparatus. Fig. 2 is a section on line A--A of Fig. 1, Fig. 3 is a section 60 on line B--B of Fig. 1, Fig. 4 is a diagrammatic view of one part of the apparatus in the initial position, Figs. 5 and 6 are detail views of parts of the apparatus in the operative positions. 65

The disks 1, 1', 1'' serving for coupling or bringing into action the coin ejectors are provided with projections I, II, III, IV, V, VI, VII, VIII, IX, and are rotatably mounted upon a shaft 2. They are connected with gears 3, 3', 3'' (Figs. 1 and 2) and are moved in accordance with the amount of change to be given, whereby corresponding projections of the disks are brought into the operative position. In its operative position the projection I of the disk 1 serves for coupling or bringing into action the delivery device of the 1-pfennig pieces, the projection I of the disk 1' serves for coupling or bringing into action the delivery device of the 10-pfennig pieces, the projection I of the disk 1'' serves for coupling the delivery device of 1-mark pieces. 70 In a similar manner the projection II of the disk 1 serves for coupling or throwing in the delivery device of the 2-pfennig pieces, the projection II of the disk 1' for coupling or throwing in the delivery device of two 10-pfennig pieces, the projection II of the disk 1'' for coupling or throwing in the delivery device of two 1-mark pieces and so on. 75 The delivery devices of the operation and the manner of coupling the same to the driving means are described in my copending application Serial No. 749,170, filed February 18, 1913, and do not form the subject of the present invention. Each disk corresponds to a certain figure of the minuend, that is to say, the disk 1 corresponds to the units, the disk 1' to the figure representing the tens, the disk 1'' to the figure indicating the hundreds, and so on. The disk 1' is therefore of a higher order than the disk 1, and the disk 1'' is of a higher order than the disk 1'. 80 85 90 95 100 105

The setting of the disks 1, 1', 1'' into the operative position for delivering a certain change may be effected in some cases by means of suitable operating member or slides 4, 4', 4'' alone, or it may in other 110

cases take place through the intermediary of ratchet gears which actuate pawls 5', 5" coöperating with ratchet gears 6', 6" of which the ratchet gear 6' is connected to the disk 1' and the ratchet gear 6" is connected with the disk 1".

The operating members or slides 4, 4', 4" serving for setting the disks are provided with pointers 7 which move over suitable scales 8, 8', 8" having suitable divisions marked from 0-X. The scale 8 corresponds to the disk 1, the scale 8' to the disk 1', and the scale 8" to the disk 1". For the purpose of transmitting the movement of the slides 10 scales 4, 4', 4" to the disks 1, 1', 1", the former are provided with toothed racks 9, 9', 9" into which may engage gears 10, 10', 10" which are rotatably mounted but longitudinally indisplaceable upon a shaft 11 which 15 may be moved longitudinally by means of a knob 12 or the like. In Fig. 1 the gears 10, 10', 10", are shown in full lines in their inoperative position, the operative positions being indicated by dotted lines. In the latter positions the gears 10, 10', 10" engage on the one hand into the racks 9, 9', 9", and on the other hand into the racks 13, 13', 13", which latter are connected with racks 14, 14', 14" engaging into the gears 3, 3', 3". If for instance the slide 4 is moved to such an extent as to cause the pointer 7 to travel from 0 to II over the scale 8, the drum 1 is moved forward from its initial position two-tenths of a revolution by means 20 of the gear 10 and the racks 9 and 13. If the slide 4 be moved three divisions, the corresponding drum is moved three-tenths of a revolution, and so on.

If, for instance, the amount of purchase 25 is 3 pfennigs and the amount paid is 5 pfennigs, so that 2 pfennigs should be paid by the apparatus as change, the drum 1 is set as follows: The slide 4 is first set in accordance with the amount of purchase, that 30 is, it is moved from the zero position until the pointer 7 is opposite division III on scale 8. The gears 10, 10', 10" are now moved into the dotted position and the slide 4 is set in accordance with the amount paid, 35 that is, it is further moved until its pointer 7 is opposite V on scale 8. During the latter movement of the slide 4 the drum 1 has been moved from the zero position two-tenths of a revolution, so that its projection II is now 40 in the operative position. The drums 1' and 1" have remained in their initial positions, that is in such positions in which their projections IX are in the operative positions. They must now be moved into the zero position in order that the delivery devices corresponding to pfennigs tens, marks and 10 marks should remain inoperative, and in order that the proper change consisting of 2 pfennigs should be delivered. The 45 drums 1' and 1" therefore receive by a sup-

plementary device an additional movement corresponding to one-tenth of a revolution. For this purpose coupling disks 15', 15" are mounted upon a shaft 51 (Fig. 4) so as to be freely revoluble thereon but immovable longitudinally. These disks are adapted to be coupled with other coupling members 16' and 16". The latter coupling members are non-revolubly but longitudinally displaceably mounted upon the shaft 51, and are provided with pins 17 which upon the movement of the coupling parts 16' and 16" enter into the holes or openings of the coupling disks 15' and 15". The coupling disks 15' and 15" are provided with slots 18 into which take pins 19 of slidably mounted rods 20' and 20". The rods 20' and 20" are provided with pawls 5' 5". Upon the shaft 51 is arranged a crank 21. When the crank is moved in the clockwise direction the coupling members 16' and 16" carry with them the coupling disks 15' and 15" so that the rods 20' and 20" are moved causing the pawls 5' and 5" to operate the ratchet wheels 6' and 6" and also causing the corresponding drums to be rotated forwardly one-tenth of a revolution, whereby in accordance with the example referred to these drums are moved into the zero position. The drums must of course after the object of this adjustment has been attained, be returned into the initial positions. The rearward movement is obtained by a spring o. In order to prevent the drums after they have been set rotating backward under the influence of the spring o, locking pawls p are provided which engage the ratchet wheels. These locking pawls p are operated by a cam shaft r, which latter may be rotated by means of a crank s. If the pawls are brought out of engagement with the ratchet wheels by turning the cam shaft r, the drums rotate backward under the influence of the spring o until a pin t (see Fig. 2) fixed to the drum strikes against the arm q which is rotatably mounted at u and rests against a fixed stop w. The projection holds the drum in the initial or zero position.

If, for instance, a 10-pfennig piece be paid in and the amount of purchase be 3 pfennigs, the operation is as follows: The slide or operating member 4 is moved from 0 to 3. The gears 10, 10', 10" are then moved into the position indicated by dotted lines and the slide 4' is moved from 0 to I, and the slide 4 is moved from III to X. This operation causes the drum 1' to be moved into the zero position and the drum 1 is moved into a position in which the projection VII is in the operative position. In order that the drum 1' should not upon the turning of the crank 21 be wrongly moved from its zero position, the following arrangement is provided: The slide 4' is provided or con- 130

connected to a toothed rack 22' which possesses 9 teeth and serves for throwing the coupling member 16' out of engagement with the coupling disk 15' whenever the slide 4' is moved from the zero position to either I, II, or III or any other point up to IX upon its scale, as shown in Fig. 6. For this purpose the toothed rack 22 engages upon movement of the slide 4' with a projection 23' of a lever 24' which is pivoted at 25' and is connected to a forked lever 27' which takes into a groove 26' of the coupling member 16'. By moving the slide 4' to the position I of its corresponding scale, the coupling 15', 16' has therefore been released (Fig. 6). If the crank 21 is now moved in the clockwise direction, the pawl 5' and the drum 1' are not operated, and the latter drum therefore remains in the zero position. The drum 1'', however, has been moved forward one-tenth of a revolution by the turning of the crank 21, it is therefore in the zero position, so that the proper change consisting of 7 pfennigs will be delivered. After the crank 21 has been turned the coupling members 16', 16'' must always be returned into the coupling position. This is effected by the following device: Upon a longitudinally movable shaft 28 which is parallel to the shaft 51 are secured arms 29 which by means of their free ends engage the peripheral portions of the coupling members 16', 16'' in such a manner as to be carried by these members when the latter are removed from the coupling disks 15' and 15''. The end of the shaft 28 is provided with a knob 30 which may be grasped when the coupling members are to be moved.

If, for instance, the amount of purchase 40 is 30 pfennigs, and if the amount actually paid consists of a 50-pfennig piece, the operation is as follows: The slide 4' is first moved in accordance with the amount of purchase from 0 to III. The gears 10, 10', 10'' are now brought into engagement with the racks 9 and 13 and the slide 4' is moved to V in accordance with the amount actually paid. The drum 1' originally had its projection IX in the operative position and 45 was afterward moved forwardly two-tenths of a revolution so that as a result of the movement imparted thereto, the projection I is in the operative position. By setting the slide 4' the lever 24' has been moved by the teeth 22' whereby the coupling 15' and 16' has been uncoupled. If the crank 21 were now moved in the clockwise direction, the drum 1' would be moved forward one-tenth of a revolution, whereas the drum 1' 50 would remain with its projection I in the operative position which would result in a wrong change consisting of 10 pfennigs being delivered. In order to obviate this error, the shaft 28 should be moved by 55 sure upon the knob 30 each time before the

crank 21 is turned, this movement causing those couplings 15', 16' or 15'', 16'' which are opened to be locked again. The shaft is then to be retracted.

If the amount of purchase be 5 pfennigs, 70 and the amount paid 1 mark, the operation is as follows: In this case the slide 4 is moved from 0 to V, whereupon the gears 10, 10', 10'' are moved into engagement with the racks 9 and 13. The slide 4'' is then 75 moved to I, whereby the drum 1'' is moved into the zero position. The slide 4' remains in the zero position as the corresponding figures of the minuend and the subtrahend are zero. The slide 4 is now moved from V to X along its scale. By the movement of the slide 4'' the coupling 15', 16'' has been uncoupled. On the other hand the coupling 15', 16' has not been set by the slide 4'. It should, however, be uncoupled as the projection IX should remain in the operative position when the crank 21 is moved in the clockwise direction as otherwise the proper change could not be delivered. For this purpose, an additional tooth 31 is provided 80 upon the slide 4. When the slide 4 is moved to X of its scale, the tooth 31 is moved against the projection 32 of a lever 33 which acts upon a rod or bar 34 guided parallel to the shaft 51, and carries the bar or rod 34 85 with it. This bar 34 is provided with a hole 35 into which may be moved a spring actuated bolt 36 which is guided in a casing 38 and is pressed by a spring 39 against a conical portion 40' of the coupling member 16'. 90 This conical portion of the coupling member 16' operates during the movement of the coupling member the bolt 36, that is, it brings the bolt 36 into engagement with the bar 34 or allows the latter to move out of 95 engagement. The movement of the bolt 36 in one direction therefore corresponds to the movement of the coupling member 16' in a certain direction and the opposite movement of the bolt corresponds to the opposite movement of the coupling member 16'. Fig. 4 shows the bolt 36 coupled to the bar 34. 100

The casing 38 is mounted in a guide way 41 parallel to the bar 34 in which it may be moved parallel to itself up to a stop 42. 105 When the lever 33 is moved by the tooth 31 the bolt 36 is moved together with the casing 38. During this movement the bolt acts upon a flange 43' of the coupling member 16' and moves the latter out of engagement with the coupling disk 15'. In order that the coupling 15', 16' should not be closed by the longitudinal movement of the shaft 28 which takes place before the turning of the crank 21, the following arrangement is provided: To the slides 4, 4' and 4'' are connected toothed racks 44, 44' and 44''. When the slides are moved to the points X of their scales at least one of these racks comes into engagement with a toothed seg- 110

ment arranged in its path. To the toothed rack 44 corresponds a toothed segment 45, to the toothed rack 44' corresponds a toothed rack 45', and to the toothed rack 44'' corresponds a toothed segment 45''. The toothed segments 45, 45' and 45'' are mounted upon a shaft 46, the rotation of which is transmitted by levers 47 to the shaft 28 thus causing the arms 29 to be turned out of the path of the coupling members 16' and 16''. In this new position which is indicated in Fig. 2 by dotted lines, the arms 29 do not come into contact with the coupling member 16', 16'' when the knob 30 is pressed, they are therefore unable to couple these members with the disks 15', 15''. After the shaft 28 has been moved by pressure upon the knob 30 and has been moved back by pulling the knob into the position indicated by dotted lines, the crank 21 is turned. Since the couplings 15', 16' and 15'', 16'' are opened, the drums 1', 1'', are not influenced by their operating gears, that is, the drum 1'' remains at 0, the drum 1' remains at IX while the drum 1 remains at V. Over the end of the bar 34 which is provided with the hole 35 takes the end of another bar 34'. This end is provided with a hole 48' which is elongated and is so placed opposite the hole 35 that the bolt 36 may enter both holes successively and may couple the bars 34 and 34' to each other. Within the hole 48' the bolt 36 may move in one direction, without carrying the bar 34'. While the coupling 15', 16' is closed, the bolt 36 couples the bars 34 and 34'. By moving the slide 4 to X, the lever 33 has been turned by the tooth 31 and the bar 34 has been moved by the bolt 36, the casing 38, the coupling member 16' and the bar 34'. The coupling 15', 16' has therefore been opened. If the slide 4'' had not been moved from the position of rest the coupling 15'', 16'' would have remained uninfluenced by the member 4'', and the bolt 36' should have remained in engagement with the bar 34' and 34''. In this case the movement of the bar 34 by the slide 4 would have caused the simultaneous movement of the bar 34'' and the bolt 36' and the uncoupling of the coupling 15', 16'. This operation takes place for instance if the amount of purchase is 1 pfennig to 9 pfennigs and when a 10-mark piece is paid in. For this purpose an additional drum corresponding to the mark-tens is to be provided.

If the amount of purchase consists of pfennig-tens for instance is represented by 90 pfennigs, and the amount paid in is 1 mark, the slide 4' is first moved to IX, the gears 10, 10' and 10'' are then brought into engagement with the racks 9, 13 and the slide 4'' is moved from 0 to 1 and the slide 4' is moved from IX to X whereby both drums 1' and 1'' are moved into the zero

position. It is essential, however, that the drum 1' should have its projection I in the operative position in order that the proper change be delivered. For this purpose the slide 4' is provided with a tooth 49' which acts upon a cam 50' of the lever 24' and rotates the latter in a direction which is opposite to the direction of rotation of the lever produced by the teeth 22'. This tooth 49' comes into action during the movement of the slide from IX to X (Fig. 5) and again couples the coupling 15', 16'. If the crank 21 is then turned, the drum 1' is moved forward from the zero position one-tenth of a revolution, and the projection I comes into the operative position.

The arrangement of the slide 4' and the arrangement of its teeth 22', 31', 49' and the parts coöperating therewith are repeated in the parts corresponding to the hundreds, thousands, etc. and the reference numbers of these parts are indicated by the indices of the slides to which they belong.

I claim:—

1. A subtracting device for change-giving apparatus comprising in combination a drum corresponding to the units of the minuend and arranged with its initial position at zero; drums corresponding respectively to the tens and hundreds of the minuend and arranged with their initial positions shifted backward by one division from the zero position; operating members adapted to be first set in accordance with the subtrahend and thereafter in accordance with the minuend; and supplementary actuating mechanism adapted after the operating members have been set in accordance with the minuend to act upon the drums and cause same to be moved forward by one division, substantially as set forth.

2. A subtracting device for change-giving apparatus comprising in combination a drum corresponding to the units of the minuend and arranged with its initial position at zero; drums corresponding respectively to the tens and hundreds of the minuend and arranged with their initial positions shifted backward one tenth of a revolution from the zero position; operating members adapted to be first set in accordance with the subtrahend and thereafter in accordance with the minuend; and supplementary actuating mechanism adapted after the operating members have been set in accordance with the minuend to act upon the drums and cause same to be moved forward one tenth of a revolution, substantially as set forth.

3. A subtracting device for change-giving apparatus comprising in combination a drum corresponding to the units of the minuend and arranged with its initial position at zero; drums corresponding respectively to the tens and hundreds of the minuend and arranged with their initial position shifted

backward one tenth of a revolution from the zero position; operating members adapted to be first set in accordance with the subtrahend and thereafter in accordance with the minuend; and means for throwing said actuating mechanism into and out of gear, substantially as set forth.

4. A subtracting device for change-giving apparatus comprising in combination a drum corresponding to the units of the minuend and arranged with its initial position at zero; drums corresponding respectively to the tens and hundreds of the minuend and arranged with their initial positions shifted backward one tenth of a revolution from the zero position; a slide to each drum, an operating member adapted to move over each slide and to be first set in accordance with the subtrahend and thereafter with the minuend, and an auxiliary actuating device for throwing each drum out of action when the operating member corresponding thereto has been moved within the first nine tenths of its scale and for throwing said drum into action when the slide is moved over the remaining tenth of its scale, substantially as set forth.

5. A subtracting device for change-giving apparatus comprising in combination a drum corresponding to the units of the minuend and arranged with its initial position at zero; drums corresponding respectively to the tens and hundreds of the minuend and arranged with their initial positions shifted backward one tenth of a revolution from the zero position; a slide to each drum; an operating member adapted to move over each slide and to be first set in accordance with the subtrahend and thereafter with the minuend; a supplementary actuating device for each drum adapted after the operating member corresponding thereto has been set in accordance with the minuend to act upon its drum and cause same to be moved forward one tenth of a revolution; and means whereby on any of the operating members being moved to the end of its scale, the actuating mechanism of the drum corresponding to the next higher figure is thrown out of operation, substantially as set forth.

6. A subtracting device for change-giving apparatus comprising a shaft, a units drum on said shaft arranged with its initial position at zero; a tens drum and a hundreds drum on said shaft arranged with their initial positions shifted backward one tenth of a revolution from the zero position; an operating member for each drum; a supplementary actuating mechanism for each drum; a second shaft parallel to first shaft; and arms on said second shaft adapted to bring the auxiliary actuating mechanism into operative position, substantially as set forth.

7. A subtracting device for change-giving apparatus comprising a shaft; a units drum

on said shaft arranged with its initial position at zero; a tens drum and a hundreds drum arranged with their initial positions shifted backward one tenth of a revolution from the zero position; a slide for each drum; an operating member adapted to move over each slide; a supplementary actuating device for each drum; a second shaft; arms on said second shaft adapted to bring the actuating mechanism into operative position; and means for throwing said arms out of operative position when an operating member is moved to the end of its slide, substantially as set forth.

8. A subtracting device for change-giving apparatus comprising a units drum arranged with its initial position at zero; a tens drum and a hundreds drum arranged with their initial positions shifted backward one tenth of a revolution; a scale for each drum; an operating member adapted to move over each scale; a supplementary actuating mechanism for each drum; toothed racks on the operating members corresponding to the tens and hundreds drums which serve to hold the actuating mechanisms in their uncoupled positions during nine-tenths of the movement of the members over their scales; and a projection on said members which serves for moving the drums into operative position, substantially as set forth.

9. A subtracting device for change-giving apparatus comprising a shaft, a units drum thereon arranged with its initial position at zero; a tens drum and a hundreds drum arranged on said shaft with their initial positions shifted backward one tenth of a revolution; a scale for each drum; an operating member adapted to slide over each scale; a second shaft; arms on said second shaft; toothed segments connected to said arms and racks on said operating members adapted when the latter are moved to the end of their scales to enter into engagement with said toothed segments which in turn move said arms into or out of operative position, substantially as set forth.

10. A subtracting device for change-giving apparatus comprising a shaft; a units drum thereon arranged with its initial position at zero; a tens drum and a hundreds drum arranged on said shaft with their initial positions shifted back one tenth of a revolution; a scale for each drum; an operating member adapted to slide over said scale; supplementary actuating mechanism adapted to move the tens and hundreds drums forward one tenth of a revolution; movable coupling members for moving the the supplementary actuating mechanism into and out of operative position; controlling surfaces on said coupling members; a series of bars; spring loaded bolts controlled from said controlling surfaces and adapted to be kept in engagement with said bars when

said supplementary actuating mechanism is in operative position; and means on the operating members being moved to the ends of said scales for rendering the supplementary actuating mechanism inoperative and for disengaging said bolts from said bars, substantially as set forth.

In testimony whereof I have signed my name to this specification in the presence of two subscribing witnesses.
